UNITED STATES PATENT OFFICE.

JAMES L. GASKILL, OF FORT WORTH, TEXAS, ASSIGNOR OF ONE-THIRD TO JOSEPH G. WESSENDORF AND ONE-THIRD TO GEORGE E. IRWIN, OF HANDLEY, TEXAS.

RELEASING DEVICE FOR BURIAL-VAULT CORES.

No. 909,394.

Specification of Letters Patent.

Patented Jan. 12, 1909.

Application filed September 11, 1908. Serial No. 452,593.

To all whom it may concern:

Be it known that I, JAMES L. GASKILL, a citizen of the United States, residing at Fort Worth, county of Tarrant, and State of 5 Texas, have invented certain new and useful Improvements in a Releasing Device for Burial-Vault Cores, of which the following is a specification.

This invention relates to devices for releasing the interior cores of burial vaults and more particularly to means for moving the cores to allow for shrinking of the vaults, and the object is to provide simple and inexpensive devices for withdrawing and holding 15 the cores of burial vaults at any desirable position so that the cores can be moved sufficiently to allow the vaults to shrink and to hold the cores rigidly at any position to which they may be withdrawn from the 20 vault.

Other objects and advantages will be fully explained in the description and the invention will be more particularly pointed out in the claims.

25 Reference is had to the accompanying drawings which form a part of this application and specification.

Figure 1 is a plan view of the devices constituting my invention. Fig. 2 is a vertical 30 section along the line $x-x$ of Fig. 1.

Similar characters of reference are used to indicate the same parts throughout the several views.

The invention is illustrated in connection 35 with the molds of a vault-making plant. A frame for supporting the exterior molds consists of the side beams 1 and 2 and cross-beams 3 and 4 which are securely attached to the side beams 1 and 2. This frame supports 40 the exterior molds 5 and also supports the formed vault 6. The interior molds or core 7 is supported on vertically movable cross-beams 8 which move vertically in slots 9 in the side beams 1 and 2. The cross 45 beams 8 are supported on hand-screws 10 which operate through bearing beams 11, two hand screws operating through each bearing beam. The bearing beams are suspended from the side beams 1 and 2 by 50 means of hooks or hangers 12 which pass around under the beams 11 and then extend upwardly and engage the side beams 1 and 2. The beams 8 may be elevated or lowered by turning the hand screws 10. The slots or 55 grooves 9 in the side beams form ways or

guides for the supporting beams 8. The hand-screws 10 and the bearing beams 11 coöperate to hold the core 7 at any desired elevation. The core 7 is forced out of the formed vault by hooked bolts 13 operating 60 through draw beams 14. The draw beams 14, when in operation, rest against the bottom of the side beams 1 and 2. The hooked bolts 13 engage coöperating hooks or staples 15 which are mounted in or attached to the 65 core by inserting the same into cross pieces 16 which are rigid with the core 7. Nuts 17 are used to draw the hooked bolts 13 down through the draw beams 14 when the core is to be loosened from the formed vault. It 70 will be apparent that the draw beams with their hooked bolts can be used with different frames so that the draw beams can be removed when the frame is used to move the formed vault to a storage place. The supporting 75 beams 8 with the bearing beams 11 and hand-screws 10 are also removable from the frame for the same reason. The frames are thus separable from the operating mechanism.

The operation is simple. The core is adjusted by means of the supporting beams and the hand screws. The exterior molds are then placed about the core. The material for forming the vault is put in place. When 85 the material is partly dried or set, the core may be drawn down slightly or as much as may be necessary by the nuts 17. The hand screws 10 will have to be turned also so that the supporting 8 will be lowered. The core 90 can thus be lowered to any distance desired to allow the newly formed vault to shrink and at whatever distance the core is lowered it is fixed against movement until it is necessary to lower the core again. In this manner the vaults are prevented from cracking. The frame which carries the vaults and the exterior molds may be mounted at such elevation as may be necessary to permit the core to be removed from the bottom of the 95 frame. It is apparent that the devices herein shown may be used with either rigid cores or knock-down cores.

Having fully described my invention, what I claim as new and desire to secure by 105 Letters Patent, is,—

1. A core releasing device for burial vaults comprising a supporting frame for the vault having vertical guide ways, core supporting beams movable vertically in said guide ways,

bearing beams suspended on said frame, hand-screws operating through said bearing beams to move said core supporting beams vertically, and means for causing said core to follow said core supporting beams downwardly.

2. A core releasing device for burial vaults comprising a supporting frame for the vaults horizontally disposed and having vertical 10 guide ways, core supporting beams movable vertically in said guide ways, means for

moving said beams vertically, draw bars to bear against the underside of said frame, and hooked bolts and nuts therefor for drawing said core towards said supporting beams. 15

In testimony whereof, I set my hand in the presence of two witnesses, this 2nd day of September, 1908.

JAMES L. GASKILL.
